CAN OPENER AND SPOUT

Alan M. Lyon, New Haven, and Donald L. Scott,
Devon, Conn.

Application March 5, 1946, Serial No. 652,099

4 Claims. (Cl. 222—90)

1

This invention relates to combined can openers and pouring spouts.

An object of the invention is to provide a simple, small and compact, easy-to-operate combination can opener and pouring spout.

Another object of the invention is to provide a combination device as above outlined, which is extremely easy to clean.

A further object of the invention is to provide a can opener and pouring spout as above which is reliable in operation, and is very economical to manufacture.

These and other objects are accomplished, in the specific embodiment of the invention illustrated herein, by the provision of a molded elongate tubular body having rigidly secured at one end a hook for engagement with the bead at the edge of a can, and having adjacent the said hook a spike so shaped and positioned that it will pierce the end of the can when the body is swung upward about the bead while the latter is engaged by the hook.

Thus, the operation of puncturing the can may be quickly and conveniently carried out, since it involves merely applying the hook to the can edge so that the bead thereof is engaged, and then swinging the body of the device upward and inward over the can, using the hook and bead as a fulcrum. The spike of the device is of short length as compared with the body length, and as a result a considerable favorable leverage is obtained. Also, the body acts as a convenient handle during the piercing operation, and consequently, since a firm hold may be had on the body and since a substantial leverage is provided, the operation of piercing the end of the can may be easily accomplished, without the expenditure of any considerable force.

The hook-carrying end of the body is provided with spring detents so that at the termination of the piercing movement of the body the latter will be automatically held in pouring position over the pierced opening in the can end. The body also has resilient gasket means which automatically seals the hook-carrying end thereof to the can along an area surrounding the pierced opening, when the body is in pouring position, the seal effectually preventing leakage of the contents of the can during the pouring operation. Thus the device is extremely convenient to use.

The tubular body of the device is relatively short, and is of a convenient, small diameter to enable it to be readily gripped in the hand, and since the hook and spike are of small size, the entire device is extremely compact and small, not requiring any considerable space in storage.

In the specific embodiment of the invention illustrated herein, the tubular body is molded of

2

plastic material, and the hook and spike are formed as part of a single metal stamping in the form of a thimble which is incorporated and embedded in the body at the time of the molding thereof. The sealing means comprises a simple rubber ring which is carried by a thimble at the end of the molded body, and the detent means comprises a pair of leaf springs mounted in the thimble and embedded in the body during the molding of the latter. Thus a novel and unique, advantageous arrangement of plastic and metal components is provided. The parts of the device are thus few in number and of simple and sturdy construction, so that manufacture may be carried out very economically without sacrificing reliable, convenient operation and long useful life.

Due to its simplicity, the device may be quickly and conveniently cleaned after each use, either by merely rinsing it in water, or else by washing and cleaning it with a brush which may be passed through the thimble and molded body without difficulty.

Other features and advantages will hereinafter appear.

25 In the accompanying drawings:

Figure 1 is a side view of the can opening and pouring device of this invention, shown as being applied to a can which latter is illustrated in fragmentary section.

30 Fig. 2 is a side view of the device after the end of the can has been pierced, the device being automatically held in position for pouring.

Fig. 3 is a fragmentary sectional view of the device along line 3—3, looking in the direction of the arrow of Fig. 2, the can being again shown in fragmentary section.

35 Fig. 4 is an axial section of the device on an enlarged scale, and

Fig. 5 is an end view of the device.

40 The combined can opener and pouring spout, as constructed in the specific embodiment of the invention illustrated herein, comprises a molded plastic, elongate tubular body 10 having a slightly curved shape longitudinally, the body having a bore 11 and being formed at one end 12 to function as a spout.

According to the invention the body 10 carries at its other end 13 and within the bore 11 thereof a metal stamping 14 comprising a tubular body portion or thimble 15 having a curled arm or hook 16 lanced outwardly therefrom, and having a flat projection or spike 17 extending axially from the outer end thereof.

45 Preferably, as shown in Fig. 4, the body portion or thimble 15 and hook 16 are molded and embedded in the end 13 of the body 10 so as to form a rigid unitary device therewith. The end 18 of the spike 17 is made pointed, and is bent at

a slight angle as shown to facilitate its piercing and cutting the end of a can.

Referring to Fig. 1, the hook 16 and spike 17 are so shaped and located that when the hook is applied to a can 19 it may engage the bead 20 at the edge of the can, with the spike 17 extending across the end 21 of the can. Thus when the body 10 is grasped and swung upward, fulcruming about the bead 20, the tip 18 of the spike 17 will pierce the end 21 of the can, and as the movement of the handle 18 is continued, the spike will cut an opening, shown at 22 (Fig. 2) in the can end.

Preferably, as shown in Figs. 1 and 2, the body 10 of the device is cut away at 23 to provide substantial clearance for the bead 20 of the can during the piercing operation.

For the purpose of automatically holding the body 10 in the operative or pouring position shown in Fig. 2, the thimble 15 has a pair of opposite, bifurcated projections 24 extending from the end, the said projections accommodating the ends of wire or leaf springs 25. The springs 25 pass through apertures 26 in the thimble 15, and the end portions 27 of the springs are embedded in the end portion 13 of the body 10. The wire springs 25 are preferably located in the thimble 15 prior to the molding of the body 10, and are rigidly and permanently secured in place by the molding operation.

As shown in Fig. 3, the wire springs 25 are formed with eyes 25a at their outer ends, the said eyes extending into the slots of the bifurcated projections 24 of the thimble 15 and projecting from the slots so as to engage the opposite cut edges of the opening 22 in the can, thereby automatically maintaining the spout in the operative or pouring position upon the completion of the piercing movement.

In order to seal the end portion 13 of the body 10 to the end 21 of a can and prevent leakage, a rubber sleeve 28 is provided, carried on the thimble 15, the edge 29 of the sleeve being positioned for sealing engagement with the end of the can as shown in Fig. 2. Preferably the edge portion 30 of the body 10 (Fig. 4) overlies a part of the rubber sleeve 28 to provide reinforcement for the latter.

It will thus be seen that the can opener and pouring device of the present invention is compact and small in size, and has few parts all of which are of simple and sturdy structure. The assembly of the parts is involved in the molding of the body 10, so that after the molding, the only additional assembly operation is the applying of the rubber sleeve 28. Thus, due to the unique arrangement of the metal and plastic components of the device of this invention, it may be fabricated very economically.

The handle 10 is of a size to be easily gripped in the hand, and due to the advantageous leverage provided by the short length of the spike 17 as compared to the handle length, the operation of piercing the end of the can may be carried out with very little force, and without difficulty.

Referring to Fig. 2, when the device is in position for pouring, it is located closely adjacent the bead and edge of the can so that practically all of the contents of the latter may be discharged through the spout without any substantial quantity remaining.

Variations and modifications may be made within the scope of this invention and portions of the improvements may be used without others.

We claim:

1. A combined can opener and pouring spout comprising an elongate tubular body shaped at one end to constitute a spout; a thimble rigidly secured in the other end of the body, said thimble having an integral hook extending laterally beyond the body for engaging the bead at the edge of a can, and having an integral spike adjacent the hook and continuing from the end of the thimble to pierce the can end when the hook is engaged with the said bead and the said body and spike are swung about the bead; detent means carried by the thimble and body for engaging the pierced opening and holding the thimble-carrying end of the body over the pierced opening the can end upon completion of the piercing movement of the body; and means carried by the thimble for sealing the thimble-carrying end of the body to the can and along an area surrounding the said pierced opening.

2. A combined can opener and pouring spout comprising a molded elongate tubular body shaped at one end to constitute a spout; a metal thimble embedded and molded in the other end of the body, the said thimble having a hook extending laterally beyond the tubular body for engaging the bead at the edge of a can, and having a spike continuing from the end of the thimble and projecting from the end of the body adjacent the hook to pierce the can end when the hook is engaged with the said bead and the said body and spike are swung about the bead; detent means carried by the thimble and body for holding the thimble-carrying end of the body over the pierced opening in the can end upon completion of the piercing movement of the body; and means carried by the thimble for sealing the thimble-carrying end of the body to the can end along an area surrounding the said pierced opening.

3. A combined can opener and pouring spout comprising a molded plastic elongate tubular body shaped at one end to constitute a spout; a metal thimble embedded and molded in the other end of the body, the said thimble having a hook interlocked with and passing through the body for engaging the bead at the edge of a can, and having a spike adjacent the hook, the said spike being shaped and located to pierce the can end when the hook is engaged with the said bead and the said body and spike are swung about the bead; leaf spring means carried by the thimble and having portions embedded and molded in the body, the said spring means being shaped to engage the edge portions of the pierced opening in the can and hold the said end of the body over the opening upon completion of the piercing movement of the body; and a rubber washer carried by the thimble for sealing the latter and the thimble-carrying end of the body to the can end along an area surrounding the said pierced opening.

4. A combined can opener and pouring spout comprising a molded plastic elongate tubular body shaped at one end to constitute a spout; a metal thimble embedded and molded in the other end of the body, the said thimble having oppositely located bifurcated extensions at its outer end, having a hook for engaging the bead at the edge of a can, and having a spike adjacent the hook, the said spike being shaped and located to pierce the can end when the hook is engaged with the said bead and the said body and spike are swung about the bead; a pair of leaf springs carried by the thimble and having portions embedded and molded in the body, the said springs

extending through and being guided by the bifurcated extensions of the thimble and being shaped to engage the edge portions of the pierced opening in the can and hold the said end of the body over the opening upon completion of the piercing movement of the body; and a rubber washer carried by the thimble for sealing the latter and the thimble-carrying end of the body to the can end along an area surrounding the said pierced opening.
